(57) **CLAIM**

The ornamental design for a cutting board with measuring tray, substantially as shown and described.

DESCRIPTION

FIG. 1 is a perspective view of a cutting board with measuring tray showing our new design;

FIG. 2 is a front elevational view thereof;

FIG. 3 is a top plan view thereof;

FIG. 4 is a rear elevational view thereof;

FIG. 5 is a right side elevational view thereof, which is substantially the same as a left side view, not shown; and,

FIG. 6 is a bottom plan view thereof.
